UNITED STATES PATENT OFFICE.

CARL PETERSON, OF HUME, CALIFORNIA.

HARROW.

1,274,586.

Specification of Letters Patent.

Patented Aug. 6, 1918.

Application filed January 10, 1917. Serial No. 141,598.

To all whom it may concern:

Be it known that I, CARL PETERSON, a citizen of Sweden, residing at Hume, in the county of Fresno and State of California, have invented certain new and useful Improvements in Harrows, of which the following is a specification.

This invention relates to improvements in harrows and one object is to provide a harrow having means for automatically guiding or steering the device during operation. With the foregoing and other objects in view the invention consists in the combination and arrangement of parts to be herein-
10 after fully described in this specification, pointed out in the appended claims and illustrated in the accompanying drawing which forms a part of said specification and in which—
15

20 Figure 1 is a perspective view of the harrow.
Fig. 2 is a plan view of one steering device employed.

25 Fig. 3 is a view of the form of tooth employed.

Like reference characters denote corresponding parts throughout.

The numeral 1 denotes the frame and the numeral 2 denotes cross bars connecting the 30 sides of the frame. The sides of the frame and the cross bars are provided with teeth 3 which have threaded shanks 4 adapted to screw into threaded openings in the said frame and in said cross bars. At points 35 equidistant from one corner 5 of the frame I provide stems 6 carried by the frame and

one of the cross bars 2, said stem carrying the rudder formed of three outwardly curved teeth 7 which drag through the earth and serve to steady the device and keep it 40 running in a straight line. To the corner of the frame diagonally opposite the corner 5 a hook 8 is secured to which the team pulling the harrow is hitched. The harrow being of square formation and the pull coming from one corner of the same and the rudders being placed equidistant from the corner of the frame diagonally opposite the pull corner it is obvious that lateral movement of the device will be obviated. 50

What is claimed is:—

1. In a harrow, a square frame provided with teeth, a draft hook secured to one corner of said frame and anchors carried by two sides of said frame and spaced away from the frame corner diagonally opposite the draft-hook-corner. 55

2. In a toothed harrow, a square frame, and anchors spaced equal distances from one corner of said frame, said anchors comprising curved teeth diverging from a central stem, and said stem being carried by the harrow frame. 60

In testimony that I claim the foregoing as my own I have hereto affixed my signature in the presence of two subscribing witnesses. 65

CARL PETERSON.
